OR D 11,760

NO. 11,760

MAY 4, 1880

UNITED STATES PATENT OFFICE.

JULIUS F. QUIMBY, OF TROY, NEW YORK, ASSIGNOR TO SWETT, QUIMBY & PERRY, OF SAME PLACE.

DESIGN FOR STOVE-DOORS.

SPECIFICATION forming part of Design No. 11,760, dated May 4, 1880.

Application filed March 16, 1880. Term of patent 7 years.

To all whom it may concern:

Be it known that I, JULIUS F. QUIMBY, of the city of Troy, county of Rensselaer, and State of New York, have invented a new and ornamental Design for the Doors of Heating-Stoves, as shown in the annexed photograph, and of which the following description is a specification.

My invention of a design relates to a manner of arranging the mica lights or panes in the combustion-chamber doors of heating-stoves, and by means of their combined form and that of the sash-bars which contain them to produce an ornamental effect having distinctive features, and also in the manner and details of ornamentation upon the sash-bars, stiles, and door-frame, for a like purpose of ornamental designation.

In the accompanying photograph there is shown a stove-door having a contour to adapt itself to a stove of like form, and provided with five mica lights or panes, (designated at *a, b, c, d*, and *O*.) and the manner in which they are formed and arranged with reference to each other constitutes the leading feature of my invention of a design for the purpose specified.

The center pane or light, *O*, is shown as arched at the top and vertically longer than the panes *c d*, arranged at the sides of the former, and the two upper corner panes, *a b*, are rounded out on their lower inside corner, to coincide with the arched form of the pane or light *O*, and all the panes or lights thus arranged have sash-bars and stiles constructed for such an adaptation of form in application for ornamental effect.

Another feature of my invention of a design consists in the application of the ornamental brackets *s''*, arranged in the corners of the panes. It also consists in the ornamentation upon the surface of the sash-bars and the stile over the arched pane, and formed by the intaglio lines *y y*, parallel to the inside and outside edges of the frame and sash, and which are angled obtusely, so as to intersect, cross,

and inclose a diamond-shaped center with opposite radiate darts at the intersections, as shown at *m*, and pyramidal relief figures in the corners, as shown at *p p p p*.

Another feature of my invention consists in the ornamentation of the exterior surface of the sash-frame *P* by means of the double lines of beading shown at *L L*.

As the general effect produced by the form and arrangement of the mica panes and sash containing them would be the same whether the latter were ornamented as shown, or not, I do not condition my invention of this former feature as limited to its combination with the surface ornamentation shown, for other surface ornamentation could be applied to this same form and arrangement of mica doors without changing the general effect produced by it.

Having thus described my invention, what I claim, and desire to secure by Letters Patent, is—

1. The design for the ornamentation of a stove-door, consisting of the five mica panes or lights *a, b, c, d*, and *O*, and the sash and frame inclosing them, with the central pane vertically longer than the lower side panes, *c d*, and arched at the top above the horizontal sash-bars *t' t''*, with the upper corner panes or lights, *a b*, curved out on their inner corners to coincide with the arched top of the pane *O*, as shown and described.

2. The design for the ornamentation of a stove-door, consisting of the form and arrangement of the mica lights or panes *a, b, c, d*, and *O*, and the sash and frame inclosing them, and the surface ornamentation of the frame and sash, (designated at *y, s'', L L, m*, and *p*.) as herein described.

Signed at Troy, New York, this 18th day of February, 1880.

JULIUS F. QUIMBY.
